Specification for Design.

Patented Oct. 11, 1921.

Application filed June 10, 1921. Serial No. 476,564. Term of patent 14 years.

To all whom it may concern:

Be it known that I, GEORGE L. SCHOFIELD, a citizen of the United States, residing at Frederick, in the county of Frederick and State of Maryland, have invented a new, original, and ornamental Design for a Traction-Tread, of which the following is a specification, reference being had to the accompanying drawing, forming part thereof.

Figure 1 is a bottom perspective view of a tread showing my new design, and Fig. 2 is a top perspective view of the same.

I claim:

The ornamental design for a traction tread, as shown.

GEORGE L. SCHOFIELD.
